UNITED STATES PATENT OFFICE.

WALTER B. PAYNE, CHARLES G. TIEFEL, AND RAYMOND E. BOHRER, OF ROCHESTER,
NEW YORK, ASSIGNEES TO THE TODD COMPANY, INC., OF ROCHESTER, NEW YORK,
A CORPORATION OF NEW YORK.

PRINTING APPARATUS.

Application filed August 29, 1923. Serial No. 660,032.

To all whom it may concern:

Be it known that we, WALTER B. PAYNE, CHARLES G. TIEFEL, and RAYMOND E. BOHRER, citizens of the United States, residing at Rochester, in the county of Monroe and State of New York, have invented certain new and useful Improvements in Printing Apparatus.

This invention relates to printing apparatus and more particularly to the variety adapted for printing checks, drafts, certificates and the like, for example with a monetary value, the chief object of the invention being to provide a simple and practical machine of this variety conveniently adapted for printing an amount either spelled out in words or expressed in figures, as the nature of the work may require, or for printing an amount partly in words and partly in figures as at times desirable for reducing the length of a legend. More specifically stated, it is an object of the invention to provide apparatus of the above character comprising a plurality of type drums adapted to be selectively employed and each provided with a plurality of type forms spaced circumferentially thereon for selective use in cooperation with a platen to break the surface of the paper so that it will absorb the printing ink, together with automatic work feeding mechanism adapted for feeding the work different distances as may be required by the type forms of the different drums.

To these and other ends the invention resides in certain improvements and combinations of parts all as will be hereinafter more fully described, the novel features being pointed out in the claims at the end of the specification.

In the drawings:

Fig. 1 is a top plan view of an apparatus embodying the present invention and partly broken away for clearer illustration.

Figs. 2 and 3 are fragmentary detail views of a portion of the feeding mechanism shown in Fig. 7 but in different operating positions.

Fig. 4 is a sectional elevation on the line 4^a—4^a in Fig. 1.

Fig. 5 is a similar sectional view partly broken away on the line 5^a—5^a in Fig. 1.

Fig. 6 is a sectional view on the line 6^a—6^a in Fig. 4.

Fig. 7 is a similar view substantially on the line 7^a—7^a in Fig. 12. 55

Fig. 8 is a detail perspective view of eccentric means for supporting the type drums.

Fig. 9 is a view similar to Fig. 6 but showing the parts in different positions.

Fig. 10 is a detail perspective view of a portion of the platen means. 60

Fig. 11 shows portions of the type drum faces developed.

Fig. 12 is a bottom plan view of the apparatus partly broken away; 65

Fig. 13 illustrates one form of impression which may be made by the apparatus and in which an amount is expressed principally in figures;

Fig. 14 illustrates the impression of an amount in words; 70

Fig. 15 shows the impression of an amount expressed in both words and figures and

Fig. 16 shows a modification of one of the type drums. 75

Similar reference numerals throughout the several views indicate the same parts.

The invention is embodied in the present instance in an apparatus of the general type disclosed in the patent to Charles H. Sampson, #1315,642, dated September 9, 1919 for printing machines, in which a type drum having a plurality of type forms is rotated to bring the forms selectively to a common printing position for successively printing words of different lengths forming an expression of a monetary value, together with platen means and a variable feeding mechanism for feeding the work in connection with each impression a distance corresponding to the length of the word printed, as well understood in the art. The present apparatus is different however in that it comprises a plurality of type drums selectively employed and each having a plurality of type forms requiring successive feeding movements of the work of uniform length for the same drum but of different lengths for the different drums respectively. More specifically, one drum in the present instance is provided with types for printing figures and the other with types for printing words the latter being arranged, however, at an inclination to the drum axis and the printing line and blocked out to a uniform length, 100 as shown in Figs. 14 and 15 so that the words

thus require only a uniform feeding of the work which is different, however, from that required by the figures. The machine therefore comprises a feeding mechanism automatically adjusted by the selection of one of the type drums for feeding the work to correspond with the arrangement of the type on the selected drum.

Referring more particularly to the drawings, there is shown at 20, Fig. 4 a casing base portion having on its top a printing bed 21. Mounted on the base is an upper casing portion 22 spaced from the base at the front of the machine to provide a work receiving slot 23. Rotatably supported adjacent its end in the side walls of the upper casing portion 22 over the work slot is a shaft 24 having fixed on one end thereof outside the casing an actuating knob 25. Fixed on the shaft within the casing is a sleeve comprising two oppositely disposed eccentric bearing portions 26 and 27 on which are rotatably mounted type drums 28 and 29 respectively. These drums are of substantially the same diameter but of different lengths and the longer drum 28 has spaced circumferentially thereon a plurality of separate type forms 30 for printing lettered words adapted to be combined for expressing any monetary value within certain limits. It is to be noted that these words are arranged at an inclination to the drum axis and the printing line and blocked out to a uniform length as shown so that while the words themselves are of variable length, uniform spacing only is required along the printing line.

The other drum 29 has spaced circumferentially thereon a series of separate type forms for printing figures, as shown in Fig. 11, adapted for impressing an amount on the work as shown in Fig. 13. In the use of this type drum also the relative spacing and the feeding of the work in writing a legend is uniform, but less than that required when printing with the word type drum 28, and suitable feeding mechanism is provided for automatically feeding the work the required distance as hereafter described.

It is apparent from the above description that rotary adjustment of shaft 24 through an angle of approximately 180 degrees tends to raise one drum to an inoperative position and to lower the other to printing position, by reason of the eccentric mounting on the bearing sleeve, as illustrated in Figs. 6 and 9, and it is desirable at the same time to shift the drums longitudinally to bring the left hand end of the type forms of each to a common point as desirable, for example, when changing from one drum to another in completing a single legend as illustrated in Fig. 15. To this end shaft 24 with the eccentrics and drums carried thereby is

slidable longitudinally in its bearings, as indicated in Figs. 6 and 9, to place the types of either drum in the position described, and this longitudinal movement is preferably accomplished by providing one end 70 of the shaft with a thread 32 engaging in a nut 33 carried by the adjacent casing wall. Thus, rotation of the shaft 24 by the adjustable means or knob 25 serves to not only move a selected one of the drums eccentrically but also axially to position for printing in cooperation with platen means described below. To retain these parts in one or the other adjusted position, knob 25 is preferably supplied with a spring pressed 75 plunger 25^a, Fig. 1, engageable in recesses in a helical shoulder 25^b on the casing which may be provided with suitable indicia for indicating the positions.

The platen means comprises preferably a 85 platen lever 35, Figs. 4 and 12, having oppositely disposed trunnions 36 and 37 resting in bearings 38 and 39 on the walls of the base. The forward end of the lever is elongated and formed with a T slot or channel 40 in which is longitudinally slidable a block 41, Figs. 4 and 10, the upper side of which, projecting above the lever, comprises impression surfaces 42 and 43 for the figure and word types, respectively. Means are 95 preferably provided as hereafter described for sliding the platen on the lever in accordance with the selection of a drum to bring the appropriate platen surface to printing position.

The operating means for pivotally swinging the platen lever to produce a printing impression of the work against the type comprises, preferably, an angular extension 44, Fig. 12, on the rear end of the lever 105 carrying an adjustable screw 45. The latter engages the lower end of a plunger 46 sliding vertically in a bearing sleeve 47 carried by the casing. The upper end of this plunger supports a roller 48 engaging the periphery of a cam 49 fixed on a transverse shaft 50 rotating at its end in bearings 51 and 52 on the casing. By means of a handle 53, shaft 50 is rocked and through the cam and plunger means described rocks the 110 platen lever to effect an impression. A

spring 54, Fig. 12, fixed to the extremity of the platen lever and to the casing serves to normally return the platen lever and handle 53 to initial inoperative position. Means 115 are provided comprising a ratchet sector 55 on shaft 50 and a spring actuated pawl 56 cooperating with the ratchet to insure a full stroke of the operating lever, this operating means being constructed and functioning 120 substantially as described in said Letters Patent to Sampson.

The feeding mechanism comprises rolls 57 projecting upwardly through slots in the printing bed into contact with the un- 125

der side of the work, the rolls being fixed on a spindle 58 rotating in bearings such as 59 on the base and having fixed on its other end a ratchet wheel 60. Cooperating with the ratchet wheel is a pawl 61, Figs. 2 and 3, carried by a plate 62 swingingly supported on shaft 58, a spring 63 being provided for maintaining the pawl in cooperation with the ratchet. Plate 62 and the pawl are oscillated by link 64, Fig. 7, pivoted at one end to the plate and at the other to the lower end of a lever 65 pivotally supported at 66 on the base. Lever 65 has a lateral arm 67 with which is pivotally connected a link 68 having a stop shoulder 69 and a head 70 at its lower end. A compression spring 71 is coiled about link 68 between the head 70 thereof and an arm 72 slidably embracing the link at one end and fixed at the other on the lower end of plunger 46. A stop pin 73 carried by a fixed arm 74 limits the active stroke of the pawl 61 and by holding the pawl against the ratchet serves to hold the latter against movement except during the operation of the machine. A presser device, indicated generally at 74^a, is provided as well understood in the art. It is apparent from this construction that at each actuation of the operating means or handle 53, plunger 46 moves arm 72 downwardly and through spring 71 actuates the pawl and ratchet means for driving the feed rolls in one direction, through a distance determined by the amplitude of pivotal movement of lever 65. The movement of the latter is adjusted by a control device 75 having a plurality of stop shoulders 76 and 77 which device is positioned automatically by the selection of one of the drums for printing, as hereafter described.

The feeding mechanism and the platen means are adjusted by a common device comprising preferably a disc 78 fixed on shaft 24 and formed with an eccentric cam slot 79 in which works a follower or pin 80 on a bar 81. The latter is provided with a slot 82 slidably embracing a fixed guide pin 83 carried by the casing and the bar is further supported by the pivotal connection of its rear end at 84 with an arm 85 pivotally supported at its upper end on shaft 50. As the type drum shaft 24 is rotated arm 81 is moved longitudinally by the cam disc 78 and thus positions arm 85 in either a forward or rear position, depending upon whether the word or figure drum is selected. The lower end of arm 85 extends downwardly through an opening in the printing bed and is pivotally connected at 86 with the rear end of a forwardly extending bar 87. The forward end of the latter is formed with an inclined cam slot 88, Fig. 12, in which works a pin 89 carried by the sliding platen bar 41.

Thus as one or the other of the type drums is selected, the platen bar is automatically shifted by the means described to place the appropriate impression surface in printing position. The impression surfaces of the type and platen are corrugated or otherwise formed to break the work or paper so that it will more readily absorb the printing ink.

The adjustment of the feeding means is also accomplished by the adjustment of the bar 81 as described. The bar is provided with an upwardly projecting lug 90 having a bifurcated end, Fig. 5 engaging opposite sides of a pin 91 carried by an arm 92 of the feed controlling device 75 already described. Thus as one or the other of the drums is selected for printing the controlling device is automatically shifted to place the higher shoulder 76 or the lower shoulder 77 in position for limiting the movement of the lever 65 of the feeding mechanism, depending upon whether the figure or word type drum, respectively is being used.

The means for rotating the drums on their eccentric bearings for bringing the type forms selectively to the printing point opposite the platen comprises preferably a type selecting knob 93 on the side of the machine opposite the drum selecting knob 25. Knob 93 is fixed on a spindle 94 rotatably supported in the casing walls and having fixed at its other end within the casing a gear 95 meshing with a gear 96 on a hub 97 rotating on the adjacent end of shaft 24. Hub 97 has projecting fingers 98 slidably engaging in recesses 99 in a hub 100 also rotating on shaft 24. Hub 100 has fixed on the other end thereof an arm 101 projecting radially and carrying a spindle 102 extending through radially elongated openings 103 and 104 in drums 28 and 29, respectively. Gear 95 carries a shroud or disc 105 engaging the side of gear 96 and holding the latter against longitudinal movement in contact with the casing wall. The other end of spindle 102 is fixed at 106 in a centering wheel 107 rotatable on shaft 24. It is apparent from this construction that as the type selecting knob 93 is rotated, the hub 97 is rotated on the shaft 24 through the gearing described and rotates hub 100 through the sliding connection described in either longitudinal position of shaft 24 which latter is free to rotate in the hubs independently of the type selecting means. Rotation of hub 100 through arm 101 and spindle 102 rotates both drums for the purpose of bringing the type forms of the selected drum themselves selectively to the printing point.

The type selecting means described above is provided with an indicating device comprising a pair of dials 108 and 109, corresponding to the drums 28 and 29, respectively, which dials are preferably fixed on

knob 93 and are visible one at a time through a sight opening 110 in a plate 111. At one side of the sight opening 110 is provided a stationary index or pointer 112 and plate 111 has an extension 113 sliding on the top of the casing. The latter carries studs 114 working in slots 115 for guiding and retaining the extension and plate in place. The extension has a pair of downwardly projecting spaced lugs 116 engaging opposite sides of an angular plate 117 projecting upwardly through an opening in the top of the casing. Plate 117 has a hub 118 sliding on a rod 119 carried by the casing and the lower end of the plate engages in a slot 120 in hub 100. Thus as the latter is shifted longitudinally with shaft 24 to select a drum, plate 111 is shifted through the connections described for placing the index and sight opening over the proper dial which, of course, is marked with a series of characters.

Means are provided for centering a selected type form in printing position comprising the centering wheel 107 described above with the notched periphery of which cooperates the suitably shaped end 121 of a bar 122 having a slotted portion 123 embracing the pin 83 described above. The rear end of the bar is pivotally connected at 123 with a lever 124 the other end of which cooperates with a cam 125 fixed on shaft 50 so that at each operation of the latter the end 121 of the bar is projected forwardly and centers the drum and type form.

A means for inking the type forms comprises a pair of inking rolls 126 and 127 rotatably supported on arms 128 and 129 respectively which are pivotally supported at their other ends by bracket means on the casing, spring means being provided for normally maintaining the rolls in contact with the type, as well understood in the art. In order, however, to disengage the rolls from the type when the latter are shifted during the longitudinal movement of the drum, each arm 128 and 129 is provided with a lug carrying a pin 130 positioned to ride on the periphery of cam disc 78. The portions of the latter opposite pins 130, when either of the drums is in printing position, are cut away to allow the rolls to rest on the type. When, however, disc 78 is rotated during the longitudinal movement of the drums for replacing one with another in printing position, the higher portions of the disc engaging the pin, carry the rolls temporarily out of contact with the type during such adjusting movement.

The operation of the various parts has been described above in connection with the description of the construction so that a brief summary will be sufficient. When it is desired to employ drum 28 for printing in words, as shown for example in Fig. 14,

knob 25 is rotated in a clockwise direction, thereby shifting the drum longitudinally toward the left with the aligned left hand ends of its type forms at the left hand end of the printing position and this drum is by 70 the same adjustment shifted eccentrically downward to printing position as the other drum is retracted to inoperative position. This adjustment automatically adjusts the feeding mechanism for properly spacing the 75 words printed from this drum and also shifts the platen bar to bring its impression surface 43 to printing position under the printing opening in the bed of the machine. Having thus selected a drum the type forms 80 of the latter are brought selectively and individually to the printing point in succession by rotating knob 93, the proper manipulation of which is indicated by the index and dial brought into view by the selection 85 of the drum. After the selection of each type form, handle 53 is operated to actuate the platen to make a printing impression and also to operate the feeding mechanism for properly spacing the impressions. By 90 rotating the adjusting means or knob 25 in a counter clockwise direction, the figure drum may be substituted in printing position and its type forms brought successively and selectively to the printing point by the 95 manipulative means comprising the knob 93. The selection of this drum adjusts the feeding mechanism and shifts the platen accordingly as already described.

The invention thus provides a comparatively simple and practical apparatus for printing amounts in either words or figures or partly in one and partly in the other and thus combines in a single convenient apparatus of this character particularly adapted 105 for protecting negotiable instruments, a range of printing type of the character described commonly available only by the use of two separate machines.

We claim as our invention:

1. A printing apparatus comprising a plurality of rotary type carriers each provided with a plurality of type forms, adjustable means for moving said carriers transversely of the axis of rotation thereof to bring them 110 selectively to printing position, manipulative means for rotating a selected carrier to bring the type forms thereof selectively to the printing point, and operating means for effecting an impression of the selected type 115 form.

2. A printing apparatus comprising a plurality of type carriers each provided with a plurality of type forms, shiftable platen means for cooperation with said type forms, 120 adjustable means for moving said carriers selectively to printing position and correspondingly shifting said platen means, manipulative means for moving a selected carrier to bring the type forms thereof selec- 125

tively to the printing point opposite said platen means, and means for effecting a relative impressing movement between the selected carrier and platen means.

5 3. A printing apparatus comprising a plurality of rotary type drums each provided with a plurality of type forms, adjustable means for shifting said drums axially and eccentrically to bring the same selectively to printing position, manipulative means for moving the selected drum to bring the type forms thereof selectively to the printing point, and operating means for effecting an impression of the selected type form.

10 4. A printing apparatus comprising a plurality of rotary type drums each provided with a plurality of type forms, spaced circumferentially thereon, adjustable means for shifting said drums along and transversely of the rotary axes thereof to bring said drums selectively to printing position, manipulative means for rotating the selected drum to bring the type forms thereof selectively to a common printing point, platen means, and operating means effecting a relative impressing movement of the selected drum and platen means.

5. A printing apparatus comprising a plurality of type carriers each provided with a plurality of type forms, adjustable feeding mechanism, adjustable means for moving said carriers selectively to printing position and for adjusting said feeding mechanism, manipulative means for moving a selected carrier to bring the type forms thereof selectively to a common printing point, and operating means for effecting an impression of the selected type form and actuating said feeding mechanism.

40 6. A printing apparatus comprising a plurality of rotary type drums each provided with a plurality of type forms, spaced circumferentially thereon, adjustable feeding mechanism, adjustable means for shifting said drums along and transversely of the rotary axes thereof to bring said drums selectively to printing position and for adjusting said feeding mechanism, platen means, manipulative means for rotating the selected drum to bring the type forms thereof selectively opposite said platen means, and operating means effecting a relative impressing movement of the selected drum and platen means.

55 7. In a printing apparatus, the combination of a pair of type carriers movable selectively to printing position and each provided with a plurality of type forms, platen means comprising a pair of impression surfaces movable selectively to printing position, feeding mechanism adjustable to correspond with the type forms of the selected carrier, manipulative means for moving the selected drum to bring the type forms thereof selectively to position for cooperation

with the platen, and operating means effecting a relative impressing movement of the selected carrier and platen surface.

8. In a printing apparatus, the combination of a pair of type carriers movable selectively to printing position, one of said carriers having a plurality of type forms for printing single characters and the other a plurality of type forms for printing groups of characters forming words arranged at an inclination to the printing line, platen means, feeding mechanism adjustable to correspond with the type forms of each carrier, manipulative means for moving the selected carrier to bring the type forms thereof selectively to position for cooperation with said platen means, and operating means effecting a relative impressing movement of the selected carrier and platen means.

9. In a printing apparatus, the combination of a pair of rotatable type drums movable selectively to printing position, one of said drums having a plurality of type forms for printing single characters and the other a plurality of type forms for printing groups of characters forming words arranged at an inclination to the printing line, platen means, feeding mechanism adjustable to correspond with the type forms of each drum, manipulative means including an indicating device for rotating the selected drum to bring the type forms thereof selectively to position for cooperation with said platen means, and operating means effecting relative impressing movement of the selected drum and platen means.

10. A printing apparatus comprising a pair of type drums, a pair of eccentrics on which said drums are rotatably mounted, means for adjusting said eccentrics rotarily and axially to move said drums selectively to printing position, and manipulative means for rotating said drums on said eccentrics for bringing the type forms thereof selectively to a common printing point.

11. A printing apparatus comprising a pair of type drums, a pair of oppositely disposed eccentrics on which said drums are rotatably mounted, means for rotarily adjusting said eccentrics and shifting the same axially to move said drums selectively to printing position, and manipulative means for rotating said drums on said eccentrics to bring the type forms thereof selectively to a common printing point.

12. A printing apparatus comprising a pair of type drums, a pair of eccentrics on which said drums are rotatably mounted, a shaft on which said eccentrics are fixed, means for rotating said shaft and adjusting the same longitudinally for moving said drums selectively to printing position, and manipulative means having an indicating device and a connection with said drums for rotating the latter and bringing the type

forms thereof selectively to a common printing point.

13. A printing apparatus comprising a pair of type drums, a pair of eccentrics on which said drums are rotatably mounted, a shaft on which said eccentrics are fixed, means for rotating said shaft and adjusting the same longitudinally for moving said drums selectively to printing position, said drums having openings therein, a spindle slidably engaged in said drum openings, and means for rotating said spindle about said eccentrics for rotating said drums to bring the type forms thereof selectively to a common printing point.

14. A printing apparatus comprising a pair of type drums, a pair of eccentrics on which said drums are rotatably mounted, a shaft on which said eccentrics are fixed, means for rotating said shaft and adjusting the same longitudinally for moving said drums selectively to printing position, feeding means adjustable to correspond with the type forms of each drum, a connection between said shaft and feeding means for adjusting the latter, and manipulative means

connected with said drums for rotating the same to bring the type forms thereof selectively to a common printing point.

15. In a printing apparatus, the combination of a plurality of rotary type drums each provided with a plurality of type forms, a platen lever, an adjustable platen actuated by said lever and having a pair of impression faces, one for each of said drums, adjustable means for shifting said drums axially and eccentrically to bring the same selectively to printing position and for correspondingly adjusting said platen, variable feeding means actuated by a connection with said adjustable means for feeding the work different distances to correspond with the selected type drum, manipulative means for rotating the selected drum to bring the type forms thereof selectively to position for cooperation with said platen, and operating means for moving said platen lever to produce a printing impression.
